Inventor:
Robert Norris.

By Jas. L. Skidmore

His Atty.

UNITED STATES PATENT OFFICE.

ROBERT NORRIS, OF WYTHEVILLE, VIRGINIA.

WINDOW-PULLEY AND HOUSING THEREFOR.

1,367,276.

Specification of Letters Patent.

Patented Feb. 1, 1921.

Application filed September 2, 1920. Serial No. 407,796.

To all whom it may concern:

Be it known that I, ROBERT NORRIS, a citizen of the United States, residing at Wytheville, in the county of Wythe and State of Virginia, have invented certain new and useful Improvements in Window-Pulleys and Housing Therefor, of which the following is a specification.

This invention relates to pulleys and a frame or housing therefor especially designed for use in connection with balanced weighted window sashes.

The prime object of the invention is to provide simple, economical, durable, efficient, and novel means for properly supporting and guiding window cords.

Another object of this invention is to so construct my improved device that it may be easily and readily mounted in place without the labor and expense of countersinking, mortising, or slotting the window frame; that it will effectually prevent any tendency of the sash cord binding on the pulleys; that it will avoid the chafing and wearing of the cords on the pulleys by any jumping of the cord into the space between the sash and the pulley flanges; that it insures against the displacement of the cord from the pulleys; that it will always maintain its upright and proper position after having been secured, and that it distributes the weight of each sash and sash weight over two pulleys instead of one thereby rendering the more ready and easy manipulation of the sliding sashes usually fitted within the window frames.

A further object of the invention is to secure the device to the upper and outer face of the heading and side jamb of the window frame, respectively, so that one of the pulleys will rest in parallel alinement with the side jamb, while the other pulley rests in parallel alinement with the heading of the window frame.

The foregoing and such other objects as may appear from the ensuing description are attained by the construction, arrangement, combination and location of parts hereinafter more fully described, illustrated in the accompanying drawings, and particularly pointed out in the claims appended hereto, it being understood that slight changes in the precise form, proportions and minor details of the construction may be resorted to without departing from the spirit

of the invention or sacrificing any of the advantages thereof.

In the accompanying drawings forming a part of this specification it will be seen that:

Figure 1, is a sectional elevation of the improved device embodying my invention.

Fig. 2, is a plan, showing the device partly in section and secured to the window frame, and

Fig. 3, is a perspective showing the housing detached and the pulleys removed therefrom.

Similar characters of reference are employed to designate like parts throughout the several figures of the drawings.

In carrying out my invention as illustrated I have shown in Fig. 1, my improved device secured to the upper right hand corner of a window frame. A designates the heading or upper member of a window frame and B, the side jamb of the frame, while the numeral 1, indicates a frame or housing made of any suitable metal and preferably stamped or forged from a single piece of metal by one stroke of a suitable stamping or pressing machine. Said frame or housing is preferably formed with laterally extended vertical flanges 2, each flange having an opening 3 therethrough for the reception of a securing screw or nail 4 whereby said flanges are rigidly secured to the side jamb, and laterally extended horizontally arranged flanges 5, each having an opening 6, adapted to receive suitable screws or nails 7 for fixedly securing said flanges to the upper surface of the window frame heading, said heading having an opening bored therethrough for the reception of a metallic guide sleeve 8, through which the sash cord 9 is adapted to be easily and readily guided in its up and down movement, one end of the sash cord being attached in any suitable manner to the window sash (not shown), while its other end is securely fastened to a balance weight 10.

It will be perceived that the frame or housing 1, is provided with a plurality of openings 11 within which is mounted a spindle or bearing which may be a tube, or a solid rod 12 capable of being fixed against endwise displacement by riveting the ends thereof, each of said rods 12 carrying a pulley 13 of the conventional type or kind.

It will further be seen that the frame or

housing is formed with a rounded upper and outer surface, which materially assists in passing the sash cord over the pulleys and through the said frame, as well as to prevent any displacement of the sash cord at all times, and the inner face of the housing being formed with two sets of laterally extended flanges, one set being arranged at a right angle with respect to the other, and secured to the outer side of the side jamb and header of the window frame, respectively, the tendency of the frame is to always remain in its fixed position in proper alignment with the sash cord, thereby avoiding the chafing and usual wear on the sash cord occasioned by the jumping of the cord into the space between the sash and the pulley flanges, and further, the location and arrangement of my device avoids the necessity for slotting, mortising or countersinking the window frame, which is the usual custom for the connection of pulleys and pulley frames to the window frames, and one pulley being in parallel alignment with the outer face of the side jamb and the other pulley arranged in horizontal alignment with the outer surface of the header the weight is distributed over the two pulleys, thus avoiding all tendency of the binding of the pulleys, and thereby permitting more easy and smooth operation thereof, as will be readily understood.

It will also be seen that since the sash cord passes through a metallic sleeve fitted within the header in alignment with the pulleys and housing or frame, said cord cannot get out of place and the pulleys and housing are naturally held in their proper position by the weighted sash cord, there being no tendency whatever for the housing to become unbalanced or displaced.

While I have shown but one of my improved devices for the purposes hereinbefore referred to, it will be understood that, two of such devices are employed for each window sash, two being secured on each upper and outer side of the window frame, one for the upper sash frame and another for the lower sash frame, as will be readily obvious.

Having thus described my invention what

I claim and desire to secure by Letters Patent is:—

1. A device of the character described, comprising a housing formed from a single piece of metal with a horizontal and vertical extension, each extension having formed integral therewith a laterally extended flange at each side thereof forming a portion of the inner face of said housing and adapted to be secured to the outer face of the heading and side jamb of a window frame, respectively, and a pulley secured within each of said extensions.

2. A device of the character described comprising a housing formed with a rounded upper and rear outer surface and with vertical laterally extended flanges and horizontal laterally extended flanges, said flanges being secured to the outer surface of the side jamb and the outer surface of the heading respectively, and a pulley secured within the housing in parallel alignment with the vertical flanges, and another pulley secured within the housing in parallel alignment with the horizontal flanges.

3. A device of the character described comprising a housing formed of a single piece having a rounded upper and rear surface with vertical laterally extended flanges and horizontal laterally extended flanges forming the inner face of a portion of said housing, said flanges being fixedly secured to the outer surface of the side jamb and the outer surface of the heading, respectively, and a plurality of pulleys secured within said housing, each pulley being in alignment with said flanges.

4. A device of the character described comprising a housing formed of a single piece of metal with vertically extended and horizontally extended flanges arranged at a right angle with respect to each other, said flanges being secured to the outer face of the side jamb and the outer face of the heading, and a plurality of pulleys secured within said housing, one pulley being in parallel alignment with the side jamb, and the other pulley in parallel alignment with said heading.

ROBERT NORRIS.
